UNITED STATES PATENT OFFICE

119,892

DESIGN FOR A COMBINED DIAL AND ESCUTCHEON FOR COMBINATION LOCKS

Paul Ressinger, Chicago, Ill., assignor to Dudley Lock Corporation, Chicago, Ill., a corporation of Illinois

Application February 7, 1940, Serial No. 90,100

Term of patent 14 years

To all whom it may concern:

Be it known that I, Paul Ressinger, a citizen of the United States, having residence in the city of Chicago, county of Cook, and State of Illinois, have invented a new, original, and ornamental Design for a Combined Dial and Escutcheon for Combination Locks, of which the following is a specification, reference being had to the accompanying drawing, forming a part thereof.

In the drawing:

Fig. 1 is a front elevation of a combined dial and escutcheon for combination locks embodying my new design.

Fig. 2 is a side elevation of the same.

I claim:

The ornamental design for a combined dial and escutcheon for combination locks, substantially as shown.

PAUL RESSINGER.
